(57) **CLAIM**

The ornamental design for a firearm trigger, as shown and described.

DESCRIPTION

FIG. 1 is a rear, top, left side perspective view of a firearm trigger in accordance with my new design;

FIG. 2 is a front, top, left side perspective view thereof;

FIG. 3 is a left side view thereof;

FIG. 4 is a right side view thereof;

FIG. 5 is a rear view thereof;

FIG. 6 is a front view thereof;

FIG. 7 is a bottom view thereof; and,

FIG. 8 is an enlarged left side view of the firearm trigger shown of a rifle which forms not part of the claimed design. The broken lines in the Figures are for illustrative purposes only and form no part of the claimed design.
